UNITED STATES PATENT OFFICE.

JAMES ALBERT HOGG, OF LOWELL, MASSACHUSETTS, ASSIGNOR TO C. G. SARGENT'S SONS CORPORATION, OF GRANITEVILLE, MASSACHUSETTS, A CORPORATION OF MASSACHUSETTS.

BACK WASHER IMMERSING AND SQUEEZING FEEDER.

Application filed August 31, 1923. Serial No. 660,459.

To all whom it may concern:

Be it known that I, JAMES ALBERT Hogg, a citizen of the United States, residing at Lowell, in the county of Middlesex and 5 State of Massachusetts, have invented a new and useful Back Washer Immersing and Squeezing Feeder, of which the following is a specification.

This invention relates to an immersing 10 and squeezing mechanism for back washers for card and comb tops, etc., and similar machines for immersing the stock, squeezing it and supporting it while feeding.

The principal object of the invention is to 15 provide a simplified means for supporting the top rolls and permitting of taking them all out of the washer collectively and conveniently instead of individually as heretofore, thus greatly simplifying the operation 20 of passing the material through as well as repairing and cleaning the machine. Also, the invention involves features of construction whereby the top and bottom rolls can be cleaned of any wool that might stick to 25 them during the process of washing, means for individually adjusting the top rolls and an improved way of supporting the weights for holding them down. The entire set of top rolls can be lifted out of the way to permit stringing up the machine and can then 30 be let down into position without necessitating any adjustment which is an important improvement.

Other features and advantages of the invention will appear hereinafter.

Reference is to be had to the accompanying drawings, in which

Fig. 1 is a side view of a back washer provided with a preferred embodiment of 40 this invention;

Fig. 2 is a plan of the same; and

Fig. 3 is a side view of the supports for the top and bottom rolls on enlarged scale showing some modifications.

Ordinarily, the top rolls of a back washer 45 of this kind are individually mounted and individually weighted. They are also individually weighted. This necessitates the taking out of these heavy rolls separately whenever the sliver is to be strung through the machine and also in case of repairs or cleaning. This is a long process consuming considerable time.

In order to avoid this difficulty, I have

provided the back washer 10 with a pivot 55 rod 11 extending transversely on which is pivoted a frame 12 having its ends at opposite sides of the washer. This frame is provided with a series of bearings 13 mounted in radial slots 14 in the frame and adjusted by screws 15 individually and radially. 60 These bearings carry the studs or shafts 16 of the top rolls 17. These top rolls therefore are all supported on this frame 12. They are arranged on the arc of a circle and although they are individually adjustable, they are collectively removable from the machine by swinging the frame 12 upwardly 65 from the position shown in Fig. 1 in full lines to that shown in dotted lines. The frame 12 is weighted at both ends by two sets of weights 18 mounted on studs 19 located on the two end frames. These weights exert their pressure on the whole set of top rolls 70 and it is a comparatively simple matter to 75 change them to secure more or less weight. I provide the frame 12 with a handle 21 for raising and lowering it.

I have also shown the set of bottom rolls 20 mounted in fixed bearings and arranged 80 around the arc of a circle concentric with that on which the top rolls are mounted so that each top roll contacts with a bottom roll when the device is in operation and exerts its pressure in a radial direction. I 85 also provide under the bottom rolls a concave perforated bottom plate 22 and above the top rolls a similar shaped perforated top plate 23. For the purpose of cleaning the two sets of rolls from any wool or fiber that may 90 stick to them or wind around them, I provide angular cleaning strips 24 at the top and bottom preferably extending along each roll so that the material will never go around these rolls. I can, if desired, as shown in 95 Fig. 3, form the bottom perforated plate 22 in undulating form to assist in preventing the passage of the material or sliver around the rolls. This can be used without the cleaning strips 24 if desired.

I have also shown the guide rolls 26 usually employed. The rest of the machine is not illustrated but of course it is used with the ordinary main squeeze rolls and feed stand rolls.

This constitutes an immersing mechanism for forcing the stock down below the surface of the liquor, pressing it under consid-

erable weight afforded by the weights 18 so as to squeeze the stock and cause its full saturation while feeding it to the main squeeze rolls. The rolls which accomplish 5 this object are suspended by the pivoted swinging frame and they are located in radial position preferably. The adjustable bearings 13 are provided to create the proper contact with the bottom rolls. The 10 bottom rolls are gear driven if desired and located radially inside the back washer, supported by the frame or stand. The perforated sheet metal pans 22 or 22^a are provided ordinarily as guards to assist in conveying the stock. If the sliver fails to continue to pass between the rolls in the ordinary way the pans, especially when formed 15 in the corrugated shape shown in Fig. 3, assist in holding it against the rolls so that it will continue on in its usual path. The strips 24 act either in conjunction with this corrugated pan, or without it, to strip the material off the rolls if it starts to wind 20 around them.

25 In this way it will be seen that the above mentioned objects are secured and especially that the top rolls can be removed from the washer by a single operation and kept out of the way while the sliver is being strung 30 through the machine or for any other purpose and then they can be put down again without readjustment and will come into proper contact with the bottom rolls to secure efficient operation. The fact that re- 35 adjustment of the individual rolls is not necessary is very important as it saves much time.

Although I have illustrated and described only two forms of the invention, I am aware of the fact that other modifications can be 40 made therein by any person skilled in the art without departing from the scope thereof as expressed in the claims. Therefore, I do not wish to be otherwise limited to the details herein disclosed but what I do claim 45 is:—

1. The combination with a backwasher for card and comb tops and the like, of a set of squeeze rolls mounted to rotate on stationary axes comprising top and bottom sets 50 of rolls, and means whereby the entire set of top rolls can be lifted from the bottom rolls and reset in the same fixed relationship against them without adjustment.
2. The combination with a backwasher, of 55 a set of bottom rolls, a frame pivotally mounted above them, adjustable bearings on the frame and a set of top rolls carried by said bearings and individually adjustable on said frame, whereby when the frame is 60 raised and lowered again, there will be no necessity of readjusting the rolls.
3. The combination with a washing machine, of a set of bottom rolls mounted in 65 stationary bearings therein in the arc of a circle, a set of top rolls arranged individually adjustable in a radial direction and means for simultaneously lifting all the top rolls about an axis beyond one end of the 70 set of rolls without interfering with their adjustment.

In testimony whereof I have hereunto affixed my signature.

JAMES ALBERT HOGG.
